UNITED STATES PATENT OFFICE.

ADOLPH POTDEVIN, OF BROOKLYN, NEW YORK, ASSIGNOR TO POTDEVIN MACHINE COMPANY, OF BROOKLYN, NEW YORK, A CORPORATION OF NEW YORK.

PAPER-BAG MACHINE.

1,176,163.

Specification of Letters Patent. Patented Mar. 21, 1916.

Application filed November 12, 1912. Serial No. 730,973.

To all whom it may concern:

Be it known that I, ADOLPH POTDEVIN, a citizen of the United States, and resident of Brooklyn, in the county of Kings and State of New York, have invented certain new and useful Improvements in Paper-Bag Machines, of which the following is a specification.

This invention relates to machines for making paper bags, having reference, more especially, to that class of automatic machines whereby a web of paper is progressively transformed into tubing which, as rapidly as it is produced, is converted into bags of predetermined length.

The principal object of my invention is to provide, in a bag machine of the class referred to, mechanism of simple and efficient construction and operation whereby bottoms are formed on tubular bag blanks.

The invention, as generally stated, comprises various novel features of construction and organizations of mechanisms, whereby the successive operations of opening the bottom ends of the tubular blanks and orderly folding and closing the same to produce so-called "square satchel-bottoms" are accomplished rapidly and efficiently, as will be hereinafter described and claimed.

While I have herein illustrated my invention as embodied in a machine for making so-called "self-opening bags", it is to be understood that various features of the invention may be advantageously used in connection with machines for the production of other well-known types of paper bags.

In the drawings—Figure 1 is a side elevation of a bag making machine equipped with the tube-cutting mechanisms, and the bottom-forming mechanisms embodying my invention. Fig. 2 is a plan of the said tube-cutting and bottom-forming mechanisms. Fig. 3 is a longitudinal vertical section as on the line 3—3 of Fig. 2, the cylinder being partly broken away to expose the gripping devices. Fig. 3^a is a sectional detail of the adjusting means for certain cam-actuating devices hereinafter referred to, as on the line 3^a of Fig. 3. Fig. 4 is a view of the opposite side of the gripper cylinder illustrated in Fig. 3, its shaft and several other parts being shown in section. Fig. 5 is a transverse section through the stationary side folders, as on the line 5—5 of Fig. 3. Fig. 6 is an elevation of the upper forwarding roller with its fold-gripping fingers and adjuncts, the said fingers and their connections being shown at one end of the roller in vertical section. In this view the fingers are illustrated in their normal non-engaging position beyond the outer folded edges of the bag blank which is indicated by the dotted lines. Fig. 7 is a view similar to Fig. 6, showing the side fingers in raised position preparatory to their being moved toward and upon the folded edges of the bag blank. Fig. 8 is a similar view showing the fingers as in gripping position upon the bag blank. Fig. 9 is an end view of Fig. 6. Fig. 10 is a plan of Fig. 8. Fig. 11 is an elevation of the side gripping fingers and adjuncts of the gripper cylinder, showing in section that part of the cylinder in which the supporting members for the fingers are slidingly mounted, and also portions of the cams for actuating said fingers, said fingers being represented in the raised position which they occupy just before gripping the bellows-sides of the bag blank. Fig. 12 is an end elevation of Fig. 11. Fig. 13 is a view similar to Fig. 11, showing the fingers in the position which they occupy when they are withdrawn from the bag blank. Fig. 14 is an end elevation of Fig. 13. Fig. 15 is a vertical section through a part of the cylinder in the region of the gripping fingers and jaws, showing the bag blank as held by said fingers and clamped by the forward transverse gripper, and also showing the rearward transverse gripper as open and the blank being introduced thereto by the rotary tucking blade. Fig. 16 is a plan of Fig. 15. Fig. 17 is a partial end view of the cylinder, and the end flap-holding devices associated therewith, a bag blank being represented upon the cylinder with the rearward bottom flap being folded by the traveling folder roller. Fig. 18 is a sectional side elevation of one of the carrying chains for the folder roller, showing the curved guide for the chain. Fig. 19 is a detail of the cylinder showing the action of the final folding roller upon the bottom of the bag. Fig. 20 is a diagram illustrating the condition of successive blanks from the cutting station to a point in advance of the tucking devices; the leading portion of the bellows-sided tube being illustrated as gripped by the pinch rollers and about to be severed; the just pre-

ceding blank as being gripped and opened out at its leading end by the side grippers on the upper forwarding roller and cylinder to produce the lateral tucks and the up-projecting flaps for the bottom; and the leading blank as gripped upon the transverse fold lines of the bottom and with the rearward flap extending upward in position to be acted upon and folded down by the traveling folder roller. Fig. 21 is a diagram illustrating the condition of the bottom portion of the tube as it is being carried through the side folders by the cylinder. Fig. 22 is a plan of Fig. 21. Fig. 23 is a sectional elevation of the forwarding roller as equipped with a modified form of finger gripping devices. Fig. 24 is an end view of Fig. 23, showing a part of the adjacent cylinder and one of its gripping fingers which co-act with the gripping devices of the forwarding roller in producing the lateral tucks of the bag bottom.

1 designates the main supporting frame which is of suitable shape and size for its intended purpose.

2 is the main driving shaft journaled in suitably-located bearings in the sides of the main frame. At one end of the frame is mounted the roll of paper (A, Fig. 1) from which the bags are to be made, which paper is impelled to suitable pasting, forming and slitting devices by means of which it is progressively converted into a bellows-sided tube having at prescribed intervals pairs of parallel longitudinal slits at and transversely of which the tube is periodically severed in order to convert it into bag blanks preparatory to the bottom forming operations upon the forward slitted portions of the successive blanks. Inasmuch as the means for converting the paper into the bellows-sided and slitted tubing is old, and as my present invention concerns especially the treatment of the tubing after it has been produced, it is not deemed necessary herein to show or describe in detail the tube-forming and slitting mechanisms other than to indicate their general arrangement in respect to the cutting and bottoming devices. (See Fig. 1).

At the delivery end of the tube-forming mechanism projects the usual forming plate 3 which is substantially equal in width to the internal width of the tube and which plate is incased by the tube during its travel. The free edge of this plate extends at a right angle to the path of travel of the tube, or substantially so, and is preferably serrated as at 4. Immediately above the plate 60 and slightly in rear of its serrated edge is a bar 5, the forward edge of which is also preferably serrated, as at 6. Hence if the leading end of the tube be advanced beyond the serrated edges and be securely held, and the portion of the tube contiguous to such

edges then be forcibly raised against the latter, the upper and lower sides of the tube will be transversely severed along the lines of the serrated edges, with one side of the tube extending slightly beyond the other as 70 usual.

The progressive feeding of the leading end of the tube to and beyond the serrated cutting members is effected by a pair of rollers 7 (Fig. 3) which constitute part of the 75 usual tube-forming and slitting mechanism; which rollers are concertedly driven by appropriate gearing, including the meshing gear wheels 7^a (Fig. 1) on their respective shafts.

Forwardly of the cutting members is a pair of parallel shafts 8 provided with intermittently-acting pinch rollers 9 (Figs. 2 and 3) between which the leading end of the traveling tube extends, said rollers being provided with peripheral ribs 10 which are so disposed as to bite and clamp the tube at predetermined intervals during its travel and thus temporarily check the advancement of the tube. The ends of the roller 90 shafts 8 are provided with meshing gear wheels 11, (the upper one of which is shown in Fig. 2) the lower shaft being provided with a gear wheel 12 which is driven from a gear wheel 13 on the driving shaft through 95 an intermeshing idler gear 14. (See Fig. 1). Thus the pinch rollers are continuously driven. The timing and relation of the parts are such that the clamping of the tube by the pinch rollers is effected when the slit- 100 ed portion of the tube is in proper position for severance at the serrated members. At this juncture an upwardly-traveling bar 15 is brought forcibly against the under side of the tube, immediately in front of said members, thereby sharply severing the bag blank from the body of the tube. This bar is carried by a pair of spaced endless chains 16 which pass around upper and lower sprocket 105 wheels 17, 18 respectively. The upper 110 wheels are loosely mounted on the shaft 8 and the lower wheels are fixed to a shaft 19 which has its bearings in the sides of the main frame. The latter shaft is provided at one end with a gear wheel 20 which 115 meshes with and is driven by the idler gear wheel 14 above mentioned, the cooperative relation of the parts to each other being such that in each cycle of travel of the chains the bar 15 forcibly impinges against the underside of the clamped tube and effects the severance of a bag blank therefrom. As above described it will be seen that the active stretches of the chains pass between the pinch rollers and the cutting members, 120 and that as these clamping and severing mechanisms comprise continuously rotating parts they can be effectively driven at a relatively high speed.

When the tubing has been advanced into 130

position to be clamped by the rollers 9, its free end extends between a pair of drawing rollers 22, 23, one (22) of which is mounted on the main shaft and the other (23) on an upper parallel shaft 24. The periphery of the upper roller is mutilated as at 25 in order that the bag blank shall be intermittently grasped and released by the segmental acting surface 25' of the roller, such surface being arranged to grasp the blank immediately after it has been severed from the body of the tube and released by the pinch rollers 9 and being of sufficient circumferential extent to advance the blank to the bite of a pair of forwarding rollers 26, 27 which are carried by parallel shafts 28, 29, respectively, having their bearings in boxes in the sides of the main frame. The roller 23 is secured to its shaft 24 by means of a set screw 23^a (Figs. 2 and 3), in the hub of the roller, whereby said roller may be nicely adjusted about the shaft in order to set its acting surface at any predetermined position in relation to the roller 22, 25 as the length of the bag blank may require.

In the present instance the drawing roller 22 is provided with a circumferential electro-type 30 which is designed, by its rolling contact with the opposing side of the traveling bag blank, to print any suitable matter thereon. In Fig. 3 I have illustrated a couple of inking rollers 31, 32 for applying the ink to the type block, which rollers may be driven by suitable gearing.

35 The shafts of the forwarding rollers 26, 27 are provided at one side of the machine with meshing gear wheels 33, and the lower shaft is provided at the other side of the machine with a gear wheel 34 in mesh with an idler 35 which, in turn, meshes with the gear wheel 13 on the drive shaft. Thus the rollers 26, 27 are properly driven in order to advance the bag blank toward the gripper cylinder 36. This cylinder is carried by a shaft 37 which has its bearings in boxes in the sides of the main frame. On one end of this shaft is a gear wheel 38 in mesh with an idler 39 which, in turn, meshes with the gear-wheel 34 on the roller shaft 28.

50 As is understood the speed at which the tubing is fed to and across the path of the cutting and gripping mechanisms determines the length of the bag blanks, such speed being prescribed by the gearing of the feed rollers 7; and as the cylinder and forwarding roller are driven at a fixed speed relatively to each other it has heretofore been necessary to adjust them bodily toward and from the feed rollers 7 in order to adapt said forwarding roller and cylinder to receive blanks of different lengths. By the employment, however, of drawing rollers of the character above described, I am enabled simply by the rotary adjustment of the 65 roller 23 to vary its point and period of en-

gagement with the roller 22 to accord with the predetermined length of the blanks and thus accomplish their uniform feeding and delivery to the forwarding roller and gripping cylinder.

70 On the periphery of the upper forwarding roller 27 is a pair of spaced points 40 which are so located that when the leading end of the bag blank enters between and is gripped by the rollers 26, 27, the points 75 penetrate the opposing tongues formed between the parallel slits in the blank and thus positively carry the blank onward against the surface of the upper roller 27. A curved guide plate 41 (Fig. 3) arranged adjacent the upper roller, insures the upward deflection of the leading end of the blank. At a suitable distance apart on the periphery of this roller, parallel with its axis, are creasing ribs 42 which engage the opposing 80 surface of the traveling blank and, in co-action with correspondingly located grooves in the lower roller, crease the blank transversely to provide properly spaced fold lines for the bottom of the bag.

85 As the blank is being carried upward by the roller 27, the free outer end of the tongue formed between the parallel slits in the under layer of the tubular blank, springs forwardly against the opposing periphery of 90 the cylinder 36 and is there received and grasped by a pair of vibratory gripping fingers 43 which extend through a slot in the periphery of the cylinder. The under tongue just referred to is somewhat longer 95 than the other tongue and the prolonged portion of the former, extending beyond the points 40, springs outwardly and is grasped by the gripping fingers 43. These fingers are carried by blocks 44 which are clamped 100 to a rock shaft 45 having its bearings in inwardly-projecting lugs 46 on the rim of the cylinder, which shaft is provided at or near one end with an arm 47 bearing at its free end a roller 48. Normally the fingers are 105 maintained in clamping position by the torsional action of a spring 49 which encircles the projecting opposite end of the shaft and is secured to a collar on the latter and to a lug at the end of the cylinder. At predetermined intervals of their traverse the fingers are temporarily opened by the engagement of the roller 48 with suitably-disposed cams 50, 51 on a cam-frame 52 at the adjacent end of the cylinder. The cam 50 is so 110 disposed that it effects the opening of the fingers to receive the leading end of the tongue as the blank is being carried upward by the roller 27 and then permits the closing of the fingers against the tongue; and the cam 51 is so located as to effect the opening of the fingers and the release of the tongue after the blank has been impelled about half way around the cylinder and just before the operation of completing the 115 120 125 130 135

bag bottom and discharging the finished article.

The cam-frame 52 (Figs. 2, 3 and 4) comprises a segment supported adjacent to and concentric with the end of the cylinder. In the present instance the segment is provided with radial arms 53 having a segmental collar 54 which loosely embraces the shaft of the cylinder, the arms being secured to inwardly extending posts 55 bolted on the adjacent side of the main frame. The segment is provided in its sides with longitudinal grooves 56 in which are slidably fitted ribs on the cam blocks, 50, 51, respectively, and these blocks are secured to the segment by through bolts 57. By loosening the nuts on these bolts the cams can be adjusted within a large range on the segment, and may then be secured in place by tightening the nuts.

20 The bolt holes 58 in the cams are elongated in order that independent adjustment of the cams on the blocks can be effected.

The leading end of the bag blanks when its opposite layers are held to the roller 27 and cylinder 36 respectively, as above described, is opened by the gradually spreading apart of the bellows-side folds as they are carried by the oppositely moving surfaces of the roller 27 and cylinder 36; that part of the bellows-sides of the blank between the transverse fold lines being drawn apart to produce the usual lateral tucks (a, Fig. 20) which enter into the formation of the bottom portion of the bag; the forwardly projecting portions of the blank adjacent these tucks being subsequently folded in proper order and pasted together to complete the bag-bottom.

At the predetermined time the blank is disengaged from the points 40 of the roller 27 and the blank is then bodily carried onward with the cylinder 36. The means for releasing the blank from the points includes an oscillatory plate 59 which normally rests upon the periphery of the roller, in the path of the engaged end of the blank, so that such end passes over upon the plate. The forward edge of this plate is provided with spaced slots 60 into which the points are permitted to enter a sufficient distance. The plate is carried by a rock shaft 61 having its bearings in boxes in the sides of the main frame. One end of the shaft is provided with an arm 62 which rests upon a suitable cam 63 on the end of the shaft 29 of the roller 27, which cam is so shaped that it effects and permits the requisite timely oscillation of the rock-shaft and its plate, whereby the latter, when the end of the blank has passed thereon, is raised to free the blank from the points, and is maintained thus raised until the roller 27 has nearly completed its rotation.

Just before the release of the blank from the points 40 two pairs of fingers 64, 65 are

caused to bear upon the lower marginal portions of the respective bellows-sides of the blank at the outer corners of the tucks a and thus to pinch the opposing portions of the sides upon the roller 27 and cylinder 36 respectively (see Fig. 20); one pair 64 of fingers being carried by the roller and the other pair 65 by the cylinder. The fingers 64 on the roller just hold the blank sufficiently long to permit the drawing of the intervening portion of the paper taut, or substantially so, and then release the same; but the fingers 65 on the cylinder retain their hold upon the blank until the bottom has been nearly completed, as will presently appear.

By reference to Figs. 6 to 10, inclusive, the construction and operation of the tuck fingers 64 and their actuating parts will be understood. The fingers comprise metal pieces which are affixed to blocks 66 at the respective ends of the roller 27, and in line with each other. Each of the blocks is pivoted, as at 67, in the slotted or bifurcated radial extension 68 of a flanged sleeve 69 which is slidably fitted on the roller shaft 29 so as to be movable toward and from the opposing end of the roller 27, its outer movement being limited by a stop formed on or by a segmental plate 70 which is secured at its ends to distance posts 71 on the end of the roller. Preferably I provide the plate with a suitably-disposed set-screw 72 which affords an adjustable stop for the block. The sleeve is maintained normally in its outer position by means of springs 73 interposed between the same and the end of the roller. On the outer side of the pivoted block 66 is secured a piece of spring metal 75 which depends into a recess 76 in the sleeve 105 and bears against the wall 77 of the recess. When the sleeve is in its outer position, with the pivoted block bearing against the opposing stop, the spring is under tension against the wall of the recess and the fingers are resting upon the outer circumferential edges of the roller, (as seen in Fig. 6); but when the sleeve is moved inwardly toward the end of the roller the block is correspondingly moved toward and pressed against the opposing end of the roller (as seen in Fig. 8). In this movement the block, as it is removed from the restraining action of the stop, is tilted or inclined by the straightening of the spring, so as to raise the finger 115 above the surface of the roller (as seen in Fig. 7), and as the lower edge of the block contacts with the end of said roller the block is brought into position with its finger bearing upon the surface of the roller, the depending spring being at the same time pressed under tension against the wall of the recess (as seen in Fig. 8). Preferably the block is provided with a suitably-disposed set-screw 74 which affords an adjust- 125 130

able stop for the block against the opposing end of the roller, and thus permits the pressure of the finger upon the periphery of the roller to be nicely determined.

5. The inward movement of the sleeve and its appurtenances as just described is effected during the rotation of the roller 27, so that the finger will be brought gradually to bear upon and travel concurrently with the underlying folded edge portion of the bag blank. When the sleeve is retracted the block and finger are caused to resume their normal position to free the edge of the blank, the spring initially acting to tilt the
10. block and quickly raise the finger.
15. block and quickly raise the finger.

The sleeves at the respective ends of the roller are simultaneously actuated, first to grip and then to release the opposing folded edges of the blank. To this end each of the sleeves is provided at its outer end with a suitably-disposed cam projection 78 which at the proper time encounters a relatively fixed stud or roller 79 which forces the sleeve inward, such sleeve, when the cam projection 25 clears the stud or roller, resuming its normal outer position.

The studs or rollers 79 for the respective sleeves are preferably mounted on brackets 80 formed on collars 81 which are loosely applied to the shaft of the upper roller 27, and are provided with adjusting devices whereby the studs or rollers can be nicely set to the proper points of action with respect to the travel of the cam projection. 35 In the present instance each of the collars is provided with an inclined radial arm 82, the outer end of which extends adjacent to a fixed bracket 83 on the side of the main frame, and is secured to said bracket by a screw-bolt 84, the slot for which, in the arm, is elongated in order to permit limited adjustment of the arm in a vertical arc. A spring 85 secured at its respective ends to the arm and main frame tends to draw down 45 the outer end of the arm, and a set-screw 86, which is applied to that end of the arm in position to bear upon the bolt, affords a ready means whereby the arm can be very nicely adjusted in opposition to the force 50 of the spring, preparatory to the tightening of the bolt and the locking of the arm in its position of adjustment. (See Figs. 2, 3, 3^a).

By reference to Figs. 11 to 14, inclusive, the construction and operation of the tuck fingers 65 and their actuating parts will appear. These fingers comprise comparatively long metal plates which are affixed to blocks 87 at the respective ends of the cylinder in line with each other. These 60 blocks are formed on or affixed to the outer ends of two shaft sections 88, 89 respectively, which are rotatably supported in a bored projection on the inner side of the cylinder, which sections are capable of longitudinal movement relatively to each other.

They are connected by a shaft 90, which is fast to one and is slidingly fitted to a longitudinal bore in the other, the latter being slotted, as at 91, for the reception of a guide piece 92 on the shaft 90, whereby the two sections can be rotated as a unit and yet be capable of relative longitudinal movement.

Within the bore of the bearing projection, at a point intermediate the shaft sections, is secured a head 93 between the opposite sides of which and the opposing ends of the respective shaft sections are interposed springs 94 which tend to maintain the sections normally projected beyond the adjacent ends of the cylinder. (See Figs. 11 and 13). On the outer end of each of the blocks 87 is a roller 95 which at a predetermined time encounters a segmental cam 96 conveniently secured to the inner side of the main frame, said cam being constructed and arranged to press the opposing shaft section and its parts, including the finger, inward against the action of the spring 94 and to maintain them thus positioned for a prescribed period. (See Fig. 11).

The fingers are normally caused to bear upon or rest near the periphery of the cylinder, by the action of a spring 97 which is secured at its ends to a stud 98 on one of the blocks 87 and to an inwardly projecting lug 99 on the adjacent end of the cylinder. This block is provided with an inwardly-extending arm 100 bearing at its free end a roller 101 which at predetermined intervals encounters suitably located cam blocks 102, 103 on the cam ring 52, which blocks are constructed to force the arm temporarily outward in opposition to the action of the spring 97 and thus swing the two fingers 65 away from the periphery of the cylinder. (See Fig. 12). When the roller escapes the cam blocks, the fingers resume their normal bearing position. The initial end of the cam 96, and the adjacent cam 102 are properly disposed in relation to each other in order that the lifting of the two fingers shall be simultaneous, and that the combined inward and lowering motions of the fingers shall be concurrent. (See Fig. 12.) As the fingers are designed to enter the intucked portions of the blank during the spreading thereof, as above described, the elevating surface of the cam 102 is constructed and arranged to effect the raising of the fingers before they reach the gripping point, and the lowering surface of said cam, together with the inclined initial surfaces of the cams 96, are constructed and arranged to effect the combined lowering and inward motions of the fingers immediately after they have thus been raised.

The cams 96 have sufficient circumferen-

tial extent to maintain the fingers in their inward gripping position until the bottom of the bag has been nearly completed at which time the rollers escape the said cams and the fingers are retracted. (See Fig. 13). The cam 103 is disposed adjacent the terminal end of the proximate cam 96 so as to effect the requisite elevation of the fingers just before or as they are withdrawn.

10 When the blank is engaged by the two sets of fingers 64, 65, as previously described, its free up-projecting portions pass into and between a pair of inclined side folding members 105 which extend tangentially, or substantially so, to the periphery of the cylinder. When the fingers 64 release the blank as above mentioned, and the latter is being bodily carried forward on the cylinder, the folding members 105 gradually press the up-projection sides a' (Figs. 20, 21 and 22) of the blank inward and downward upon the underlying bottom portion of the blank and at the same time flatten down the adjacent end portions a^2 of the blank, so that the tongues thereof extend in opposite directions as illustrated most clearly in Fig. 22. The fingers 65 are released from the blank at or about the time they pass beyond the folding members. Each of the side folding members comprises a bar having the inwardly beveled or inclined top portion 106 and the depending side 107, the whole constituting, in effect, a fixed cam of appropriate form to impart the requisite inward fold to the contiguous portions of the traveling blank. The lower ends of the two bars are affixed to and supported by means of clamp brackets 108 depending from a suitably disposed cross-bar or shaft 109, and the opposite ends of the bars rest upon the periphery of the cylinder, and are held in position by means of adjustable clamp brackets 110 on a cross bar or shaft 111. (See Figs. 2, 3 and 5.)

111. (See Fig. 2.)
50 Mounted on the cylinder 36 in spaced relation to each other, immediately in rear of the gripping fingers 43, are two sets of transverse grippers 112, 113, which are designed successively to receive and crease the bottom portion of the blank, throughout its width, after it passes from the side folder; the respective lines of gripping being the transverse fold lines of the bottom defined by the 55 creasing ribs 42 on the roller 27 above described. The forward gripper 112 comprises a jaw bar which extends into a transverse slot 112^a in the wall of the cylinder, one side of said slot constituting one of the gripper 60 jaws. The jaw bar is affixed to a rock-shaft 114 which is journaled in lugs 115 on the inner side of the cylinder, one end of the shaft being provided with an arm 116 bearing a roller 117 which, at predetermined in-

tervals, contacts with suitably located cam-blocks 118, 119 and is thereby actuated to open the jaw in opposition to the action of a spring 120 which encircles a projecting end of the shaft and is secured to a collar on the latter and to the adjacent lug of the cylinder 70 so as to exert a torsional closing force on the jaw. The cam blocks 118, 119 are adjustably mounted, similarly to the cam blocks 50, 51 above described, on a segmental frame 52 bolted to the adjacent side of the main frame. (See Figs. 2, 3 and 15.) One (118) of the cam blocks is so arranged that when the gripper 112 is directly above the axis of the cylinder the gripper is open; and at this juncture a rotating tucking blade 80 121 of usual construction impinges upon the blank, transversely thereof, and tucks it between the open jaws of the gripper. As the blade in its rotation recedes from the in-tucked blank, the jaws forcibly grasp and 85 transversely crease the latter.

The tucker blade 121 is carried by an arm 122 on a cross-shaft 123 which has its bearings in boxes in the sides of the main frame, said shaft being actuated through a gear 90 wheel 124 in mesh with the gear wheel 38 on the cylinder shaft.

The rearward gripper 113 includes two jaws which extend into a transverse slot 125 in the wall of the cylinder. The forward jaw comprises a bar 126 which is fixed at its respective ends to lugs 127 on two annular frames 128 carried by the respective ends of the cylinder, and the rearward jaw comprises a vibratory bar 100 affixed to a rock-shaft 129 which is journaled in said lugs and is equipped at one end with an arm 130 bearing a roller 131, which at predetermined intervals contacts with the cam block 118 and another suitably disposed cam block 118^a on the frame 52^a, and is thereby actuated periodically to open the movable jaw in opposition to the action of a suitably-disposed spring 132. This spring encircles a projecting end of the shaft 129 and is secured to a collar on the latter and to the adjacent cam frame 128 so as to exert a torsional closing force on the vibratory jaw of the gripper 113.

As the gripper 113 approaches the vertical plane of the axis of the cylinder the roller of the arm 130 encounters the opposing cam 118 and is thereby actuated to open the gripper; whereupon a rotating tucking blade 133 carried by an arm on the shaft 123, impinges against the top of the blank, transversely thereof, and tucks it between the jaws of the gripper 113. This blade, similarly to its companion, passes on from the in-tucked portion of the blank, and the jaws thereupon forcibly grasp and transversely crease the latter. In virtue of the creasing or bending action of the grippers

113 upon the blank, the trailing flap portion (a^2) for the bottom springs upward after it escapes the side-folding members 106. (See Figs. 15 and 20.)

5 The annular frames are adjustable within defined limits about the axis of the cylinder so that the extent of the space between the two pairs of transverse grippers may be nicely regulated to accord with the width 10 of the bag bottom. To this end each of the frames is provided with arms 134 radiating from a hub 135 which is loosely mounted on the cylinder shaft 37, the frame being adjustably secured to said arms by bolts 136 15 passing through arc slots in the frame. The two frames are provided with corresponding peripheral gear racks 137 with which mesh pinions 138 on the respective ends of the shaft 139 which has its bearings in the arms 20 of the cylinder 36, whereby when the bolts are loosened the shaft may be partially turned, to the right or left, by means of a suitable key, so as properly to move the annular frames relatively to the cylinder 25 and thus adjust the grippers 113 carried thereby toward or from the grippers 112, as desired. When the requisite adjustment of the grippers has been effected, the frame is locked in position by the act of tightening 30 the bolts 136.

As the cylinder continues its movement with the bottom portion of the blank transversely clamped by the grippers 112 and 113, the blank is carried under a pair of depending spring fingers 142 which bear upon the marginal portions of the blank and press them snugly against the cylinder. At this stage paste is applied to the in-turned side-flaps and the leading end flap a^2 of the 35 blank by means of a rotary paste-applying device of usual construction. This device comprises a U-shaped sector head 143 mounted on a cross-shaft 144 which has its bearings in boxes in the sides of the main frame 40 and has at one end a gear wheel 145 in mesh with the gear wheel 38 of the cylinder shaft. The head is supplied with paste from a paste-pan 146 by means of an interposed feed roller 147, the shaft of which is 45 equipped with a pinion 148 in mesh with the gear wheel 145. (See Figs. 1, 2 and 3.)

When the paste has been applied as just described, a traveling folder and presser roller 149 impinges rearwardly against the 50 upstanding trailing flap of the blank and folds it down upon and into intimate contact with the bottom portion of the blank intermediate the grippers. This roller is carried by and between a pair of spaced 55 chains 150 which pass around sprocket wheels 151 on the shaft 144 and around a pair of smaller sprocket wheels 152 carried by a shaft 153 which has its bearings in adjustable boxes in the sides of the main frame

just beyond the cylinder. Curved guides 65 154, corresponding with the curvature of the cylinder, are secured to the sides of the main frame, adjacent the respective ends of the cylinder, which guides are constructed and arranged to support and guide the active 70 stretches of the chains traveling adjacent the cylinder, and direct the presser roller 149 in a path contiguous to and corresponding with the periphery of the cylinder. The chains are driven at a speed somewhat 75 in excess of the surface speed of the cylinder, and hence the presser roller as it approaches the cylinder contacts with the up-projecting flap and progressively folds it down upon and intimately presses it against 80 the bottom portion of the blank (see Fig. 17), said bar finally escaping the blank and passing outwardly around the lower sprocket wheels. The exposed pasted portion of the blank, as it hugs the cylinder, 85 passes onward and is not engaged by the roller.

At or about the time the folder and presser roller 149 contacts with the trailing upstanding portion of the blank the roller 90 of the actuating arm 130 of the grippers 113 encounters the suitably-disposed cam-block 118^a on the frame 52^a thus opening the grippers 113 and freeing the portion of the bottom clamped thereby. Immediately thereafter the roller of the actuating arm 47 of the fingers 43 encounters the suitably-disposed cam-block 51 on the frame 52 thus raising the fingers and releasing the engaged tongue. The freed unfolded portion a^2 of 100 the bottom springs partially outward from the cylinder, and when the folder and presser roller 149 escapes the bottom portion of the blank this unfolded portion impinges against a folding roller 155 which is mounted to bear against the periphery of the cylinder at a point below the lower sprocket wheels 152. This roller thus, as the cylinder rotates, imparts the final fold to the bag 105 bottom, as indicated in Fig. 19. The roller 155 is journaled in boxes in the walls of the main frame, and is provided at one end with a pinion 156 which is geared with and properly driven by a gear wheel 157 on the end of the shaft 153 through an interposed roller 110 158. (See Fig. 1.) After the final fold has been completed the grippers 112 are released from the bag by the roller of their actuating arm 116 contacting with the suitably-disposed cam block 119 on the frame 52^a, and 115 thereupon the finished bag is delivered to an off-bearing belt 159 which carries it to a 120 suitable point of discharge.

The diameter of the cylinder is preferably such that several successive blanks may be 125 progressively acted upon thereby at the same time, as is common in continuous bag making machines, and hence the cylinder is pro-

vided with a plurality of sets of complementary gripping devices 48, 64, 65, 112, 113 of the character above described; the whole being arranged in spaced relation to 5 each other throughout the periphery of the cylinder as illustrated in Fig. 3. In the present instance there are three sets of these gripping instrumentalities, which are timely actuated in their rotation by the same sets of 10 cams, that is, the cams bear a predetermined relation to each other and to the cylinder and correspondingly actuate each succeeding set of grippers during the rotation of the cylinder.

15. In Figs. 23 and 24, I have illustrated a slight modification of the gripper devices at the ends of the forwarding roller 27. In this construction the blocks 66 to which the fingers 64 are secured are pivoted to collars 20 68^a on the spring-controlled sliding sleeves 69, 69 respectively, so as to be capable of oscillation in the direction of the axis of the roller instead of toward the ends of the latter as in the first described construction.

25. Each of the blocks is held normally in a horizontal or clamping position by means of a spring 75^a which is interposed between the outer portion of the block and the collar. On the outer end of the block is a stud 160 30 bearing a roller 161 which, at proper times in the rotation of the forwarding roller, impinges against and rides under horizontal cam projections 162, 162^a on a stationary ring 163 concentric with the forwarding 35 roller, thereby tilting the block and raising the inwardly projecting finger 64 thereof outwardly beyond the periphery of the roller 27. This ring 163 is carried by the adjustable disk 81^a which is adapted similarly to the collar 81 hereinbefore described to be 40 adjusted about the roller shaft 29 in order to set the cam projections 162, 162^a in proper working position. On the inner face of the disk 81^a is an annular flange 164 which is 45 provided at a proper point on its inner edge with a projecting roller 79^a against which bears a cam head formed on the opposing end of the sliding sleeve, the cam surfaces 78^a of said head being so disposed in relation to each other and to the cam projections 162, 162^a that while the latter in conjunction with the spring 75^a are oscillating the block 50 in respect to the periphery of the forwarding roller, the sleeve is being pressed toward 55 or retracted from the end of the cylinder, thereby imparting the combined oscillatory and longitudinal movements to the finger during the rotation of the said forwarding roller. When the rollers 161, 79^a escape 60 their respective cams, the finger 64 is reversely moved from its gripping to its original position.

The ring 163 is preferably adjustably secured to the flange 164 by means of a set- 65 screw 165, the hole 166 for which in the

ring is elongated in order that said ring and flange can be adjusted circumferentially of each other to effect accurate spaced relation of the cam projections 162, 162^a and roller 79^a to each other and to the cam surfaces 70 78^a and roller 161.

I claim—

1. The combination with a forwarding member having means to engage and hold one end of a tubular blank, a cylinder provided with gripping means to engage and hold the end of the opposing layer of the blank, means for releasing the blank from the forwarding member after the leading end of the blank has been partially opened 80 by the forwarding member and cylinder, tuck fingers on said member and cylinder respectively, means for periodically actuating said fingers to engage and release the respective opposing sides of the tube, and 85 stationary side folding members into which the open leading end of the blank is advanced by the forwarding member and cylinder while the blank is held by said member and the cylinder. 90

2. The combination of a forwarding member, a gripper cylinder, tuck fingers on said member and cylinder respectively, stationary side folding members overlying said member and cylinder and positioned to receive 95 the open leading end of the blank while the blank is being carried by said member and cylinder, and means for actuating the tuck fingers to effect their engaging and releasing actions, the period of engagement of the 100 fingers of the cylinder exceeding that of the fingers of the forwarding member.

3. The combination with a forwarding roller, and a gripper cylinder adjacent thereto, of stationary side folding members overlying said roller and cylinder, said member having inclined acting surfaces with which the open leading end of the blank contacts while it is being carried by said roller and cylinder. 110

4. The combination with a forwarding roller, of pivotally mounted blocks at the ends of said roller, tuck fingers on said blocks, supports for said blocks, means for periodically moving said supports toward 115 and from the ends of the roller in a path parallel to the axis of rotation of said roller, and means for oscillating said blocks and their fingers during the movements of the supports. 120

5. The combination with a forwarding roller and its shaft, of sliding sleeves on said shaft adjacent the ends of the roller, blocks pivoted on said sleeves, tuck fingers on said blocks, means for periodically moving the sleeves toward and from the ends of the roller, and means for oscillating said blocks and their fingers during the movements of the sleeves. 130

6. The combination with a forwarding

roller and its shaft, of sliding sleeves on said shaft adjacent the ends of the roller, blocks pivoted on said sleeves, tuck fingers on said blocks, means for periodically moving the sleeves toward and from the ends of the roller, and spring connections between said blocks and sleeves, whereby the blocks and their fingers are oscillated during the movements of the sleeves toward and from the roller.

7. The combination with a forwarding roller and its shaft, of pivotally mounted blocks at the ends of said roller, tuck fingers on said blocks, supports for said blocks, springs to maintain said supports normally away from the ends of the blocks, abutment devices for periodically engaging the supports to force them toward the ends of the roller, adjusting means for said abutment devices, and means for oscillating said blocks and their fingers during the movements of the supports.

8. The combination with a gripper cylinder, of gripping fingers at the ends thereof, shaft sections for said grippers slidably and rotatably mounted on said cylinder, means tending to keep the shafts normally apart, means tending to maintain the fingers normally in contact with the periphery of the cylinder, means for periodically moving the shafts toward each other, and means for periodically raising the fingers from the periphery of the cylinder.

9. The combination with the gripper cylinder, of a transverse bottom gripper mounted thereon, a second transverse bottom gripper arranged in spaced relation thereto, end frames axially mounted on the cylinder and supporting the latter gripper, rack and pinion connections between the cylinder and the frames whereby circumferential adjustment of the frames and cylinder relative to each other can be effected to regulate the space between the transverse bottom grippers, and means for securing said frames and cylinder in their position of adjustment.

10. The combination with the gripper cylinder, gripper jaws thereon, and means for tucking a blank between said jaws, whereby said blank is creased along the base of its trailing portion and such portion is upwardly deflected, of flexible endless carriers, means whereby the active stretches of said carriers are caused to travel adjacent to and in the same direction and curvature as the periphery of the cylinder, a transverse bottom folder on said carriers, and means for impelling said carriers, whereby the folder in its travel swings the upstanding flap portion down upon and throughout the entire width and length of the blank.

11. In a paper bag machine, the combination with the gripper cylinder, gripper jaws thereon, and means for tucking a blank be-

tween said jaws, whereby said blank is creased along the base of its trailing portion and such portion is upwardly deflected, of a transverse bottom-folding roller mounted to travel adjacent thereto and in the same direction and curvature as the opposing peripheral surface of the cylinder, lateral chains carrying said roller, sprocket wheels for said chains, shafts for said wheels, and means for impelling the chains whereby the said roller in its travel swings the upstanding flap portion down upon and throughout the entire width and length of the blank.

12. The combination with the gripper cylinder, gripper jaws thereon, and means for tucking a blank between said jaws, whereby said blank is creased along the base of its trailing portion and such portion is upwardly deflected, of a transverse bottom folding roller mounted to travel adjacent thereto and in the same direction and curvature as the opposing peripheral surface of the cylinder, lateral chains carrying said roller, sprocket wheels for said chains, shafts for said wheels, means for impelling the chains whereby the said roller in its travel swings the upstanding flap portion down upon and throughout the entire width and length of the blank, a final folding roller below the chains, and means for rotating said roller.

13. The combination with the gripper cylinder, gripper jaws thereon, and means for tucking a blank between said jaws, whereby said blank is creased along the base of its trailing portion and such portion is upwardly deflected, a rotary paste-applying member adjacent thereto, a shaft upon which said member is mounted, sprocket wheels on said shaft, a lower shaft, sprocket wheels on the latter, chains passing around the upper and lower sprocket wheels, and a transverse folding roller carried by said chains and adapted to be impelled upon the opposing periphery of the cylinder whereby the said roller in its travel swings the upstanding flap portion down upon and throughout the entire width and length of the blank.

14. The combination of tube-cutting mechanism, gripping mechanism associated therewith, intermittently-acting blank-drawing mechanism beyond said gripping mechanism, forwarding rollers beyond said drawing mechanism, means on one of said forwarding rollers for temporarily engaging and holding the leading end of the blank, tuck-gripping fingers on said roller, means for periodically actuating said fingers, a gripper cylinder adjacent said forwarding rollers, gripping devices on said cylinder to engage the free end of the layer of the blank contiguous thereto, tuck gripping fingers on said cylinder co-acting with the first-named fingers to spread the leading

portion of the blank, means for periodically actuating the tuck-gripping fingers of the cylinder, stationary side-folding members overlying the forwarding rollers and the cylinder, and adapted to receive the leading portion of the blank, transverse bottom grippers mounted on the cylinder in spaced relation to each other, means for periodically actuating said bottom grippers, paste-
10 applying devices adjacent the cylinder, end

folding and pressing mechanism succeeding the paste-applying devices, and final end folding means adjacent the cylinder.

Signed at Brooklyn in the county of Kings and State of New York this eleventh ¹⁵ day of November A. D. 1912.
